CONTAINER CLOSURE

Herman M. Kulman, Atlanta, Ga.

Application October 28, 1941, Serial No. 416,781

5 Claims. (Cl. 215—40)

The present invention relates to closures for bottles and containers and more particularly to closures of the types that consist of a metal cap and a gasket interposed between the cap and the opposed end of the bottle or other container on which the closure is used, so as to form an airtight joint between the bottle and the cap.

The most common commercial practice in the bottling of carbonated soft drinks and other beverages has been to utilize cork gaskets with the metal caps of the crown or other types extant. The present dearth of cork for such use, because of its diversion for use in the national defense program, has created a demand for an adequate gasket material which, notwithstanding the national emergency, would be available in quantity at favorable cost and would have equivalent, if not superior, performance characteristics to the scarcer cork.

In the capping of bottles, particularly with present crowning machines which clamp a crown cover on the bottle mouth, the crown gaskets must have sufficient elasticity or resiliency to prevent any damage to the bottles by the pressure of the crowning machines which may run as high as 800 lbs. per square inch during crowning. The gasket must also possess sufficient resiliency to recover, i. e., to tend to spring or snap back to original uncompressed shape after the crown has been crimped on the bottle and crowning pressure has been removed in order that an effective sealing of the bottle contents may be maintained by the crown-held gasket.

There are other properties which a satisfactory gasket material for crown and other stoppers must possess:

1. It should be light.
2. It should not have taste imparting properties to impair the flavor of bottled contents, nor should it have any coloring effect.
3. It should contain no foreign matter or materials likely to fall into the bottled beverages and contaminate the latter.
4. It should be impervious to water and be unaffected by carbon dioxide (CO₂) gas or other gases.
5. It should be available commercially in quantity at favorable cost and be unlikely to come under restrictions entailed by the national emergency.

It is an object of this invention to provide gaskets and gasket material fulfilling the foregoing requirements.

Another object of this invention is to provide gaskets or cushions and material therefor which may be utilized with crown covers extant and hence used on all presently known makes of crowning machinery without any changes or adjustments thereof.

Still another object of this invention is to

provide gasket material from which the necessary gaskets may be manufactured in presently used disk or gasket-making machines.

5 A further object is to provide gasket material from which the gaskets or cushions can be manufactured simply, cheaply and in quantity.

To the accomplishment of the foregoing and such other objects as may hereinafter appear, this invention consists in the novel composition, construction and arrangement of parts herein-after to be described and then sought to be defined in the appended claims, reference being had to the accompanying drawing forming a part hereof and which shows, merely for the purposes of illustrative disclosure, preferred embodiments of the invention, it being expressly understood, however, that various changes may be made in practice within the scope of the claims without digressing from the inventive idea.

In the drawing, in which similar reference characters denote corresponding parts:

Fig. 1 is a sectional view of one form of bottle closure embodying the invention;

Fig. 2 is a bottom view of this closure;

Fig. 3 is a sectional view of a closure embodying a modified form of the invention;

Fig. 4 is a perspective view of one manner of preparing the gasket members from rods of gasket material;

Fig. 5 is a perspective view of another manner of preparing from sheets of the gasket material the compressible discs utilized with the closure of Figs. 1 or 3; and

Fig. 6 is a sectional view of the application of the invention to another type of closure.

In the drawing, 10 is an ordinary metallic cover or cap of the crown type having a convoluted rim 11 adapted to pass over and be clamped under the lip of a bottle (not shown) in well-known manner.

40 A cushioning disc 12 is arranged within the cover. This disc must possess all the characteristics hereinabove outlined and is made either entirely of peanut shells or hulls, or peanut shell or hull composition, or cotton seed hulls, or cotton seed hull composition, or bagasse composition, or a mixture of all or some of these or two of them at least, prepared as will be presently described. The material of the disc as prepared is approximately $\frac{3}{16}$ of an inch in thickness and approximately 1 and $\frac{1}{16}$ inches in circumference. With such dimensions, it fills substantially the cap 10 to a point just short of the convoluted rim 11. The disc is firmly adhered to the metal shell. In practice, this is accomplished by presently known method of assembling discs and crowns, i. e., by dropping gutta percha into the crown cup and heating it if necessary and then assembling the disc with the cap. It may be done by providing the disc with

55

a bottom coating or covering 13 which is adapted to adhere to the metal shell so that in shipment and during its presence in the crowning machine the disc will remain firmly attached to the metal cap. Suitable adherents are: gutta percha, albuminous binders such as those now used in the preparation of cork composition discs, tasteless glue and tasteless cement made from coal tar products, proteins, resins, glycerine and casein. A specifically suitable glue is "Casco" powdered casein glue, manufactured by Casein Co. of America, Div. the Borden Co., New York. Any other suitable adherent which will serve the purpose without harmful effect on the resilient properties of the disc or on the bottle contents may be used.

In conjunction with the cushioning disc 12, a facing disc 14 may be provided. This is superimposed upon the face 15 of the disc 12 which lies adjacent the bottle neck when the cover is applied to a bottle. The facing disc 14 is admeasured to cover substantially the entire surface of face 15 and is secured in place on the resilient cushioning disc 12 by use of a suitable bonding agent or adherent such as one of those mentioned above.

The purpose of the facing disc 14 is to prevent beverages coming in contact with the cushioning disc 12, thus making the latter absorption and moisture-proof. For this reason, the facing disc 14 completely covers the surface 15 of the cushioning disc. In practice, for most soft drinks, the facing disc 14 may be made of glazed paper. With beer and ale, the facing disc 14 is or may be a rubber composition material such as the commercial product known as "Pliofilm." The two discs 12 and 14 when united comprise a plied unitary disc having a cushioning layer 12 of peanut shells or hulls, or cotton seed hulls or said other materials and a facing layer 14 united therewith and fully or partly covering the outer face 15 of the cushioning layer 12. Facing disc 14 may be made of other suitable materials such as unglazed liquid-proofed paper. In other cases it may simply be a layer of suitable liquid or waterproofing material that is impervious to gases and will have no deleterious effects on the bottle contents, for example, commercial products known as "Koroseal" or "Sterilkote," produced by Bradley & Vrooman Co., Chicago, Illinois, waterproofing emulsions such as "Aridex," produced by the Du Pont Company of Wilmington, Delaware; "Migasol," produced by the Ciba Company, Inc., of New York, N. Y.; "Impregnole," produced by the General Dyestuffs Corporation, of New York, N. Y., and tasteless lacquers, proteins and synthetic and natural resins.

Other suitable facing disc material could, for example, be suitable: papers, cotton, rayon or silk or the like material impregnated with "Sterilkote" or others of the liquid or waterproofing materials just mentioned.

With some beverages, it is not necessary to provide the facing disc 14. Instead, as shown in Fig. 3, the cushioning disc 12a of identical construction and material is substituted for the disc 12. Cushioning disc 12a is liquid- or waterproofed with an agent comprising one or more of the following materials: For example, "Pliofilm" (in liquid form), "Koroseal," "Sterilkote" the aforementioned emulsions and tasteless lacquers, proteins, synthetic or natural resins, paraffin or suitable liquid vegetable waxes. The liquid- or waterproofing of the discs 12a

may be effected either by spraying the agent thereon or in some cases by dipping the cushioning disc 12a in the liquid or waterproofing agent or by otherwise impregnating disc 12a therewith. The characteristics of the agent, of course, must be such as not to destroy the cushioning and sealing properties of the disc 12a. As with disc 12 the disc 12a is adhered suitably to the metal cap 10a by a suitable binder such as that mentioned above. Disc 12a serves both as a cushion and a seal.

Cushioning and sealing discs 12 and 12a made of the materials specified herein are sanitary in all respects, more so in fact than cork discs since 15 composition cork discs are manufactured from cork scraps. Cushioning discs 12 and 12a are neater in appearance, being cleaner looking and, in addition, meet all necessary sealing requirements.

20 The discs 12 or 12a may be manufactured simply and cheaply. Preferably, they are manufactured with machinery extant, used heretofore in the production of cork discs.

Peanut shells or hulls are first comminuted by being ground in a suitable mill to a size that 25 will pass approximately 12½ mesh screen. The ground material is mixed with one or more of the binders or adherents hereinbefore described in the proportions of 20 parts by weight (uncompressed) of ground material and 10 to 15 parts by weight of binder adherent. With different binders, the percentage thereof by weight may range from 5% to 50% by weight of the ground material. After thorough mixing, the mixture 30 is packed into tubular containers (preferably of metal) and having an internal diameter equal to that ultimately required of the discs, namely, approximately 1 and $\frac{1}{16}$ inches. The contents of each tubular container is subjected to a high pressure therein ranging from approximately 40 1000 to 25,000 pounds, depending on the nature of binder and the ground material. While under this pressure, heat is applied to the tubing to raise its contents to a temperature ranging from 45 75° to 350° Fahrenheit. This temperature is maintained for a period sufficient to set the compressed contents. The heating period varies, ranging from $\frac{1}{2}$ hour upwards, depending upon the nature of the binder or adherent and the ground material. When setting has been completed, the tube is cooled slowly while the pressure is maintained. The contents are then expelled in the form of a cylindrical rod 16. This rod is then passed to a suitable slicing machine, 50 such for example, as that illustrated in U. S. Patent No. 1,259,887, issued March 19, 1918, to Charles E. McManus. This slices discs D of the required thickness for use herein and is adjustable to provide discs having the thickness of discs 12 or of discs 12a, the former being somewhat thinner to allow for the thickness of the facing disc 14.

Substantially identical procedure is employed for the preparation of discs made either of peanut shell or hull composition, or of cotton seed hulls, or of cotton seed hull composition, or of bagasse, or of bagasse composition, or of a mixture of one or more of these with others or peanut shells or hulls. Where a mixture of shells or hulls or composition is used, any suitable proportion of each material may be used.

When peanut shell or hull composition, or cotton seed hull composition or bagasse composition are referred to herein they are intended to designate respectively a mixture either of peanut

shells or hulls, or of cotton seed hulls, or of bagasse with one or more of the following ingredients: Phenolic resins and other synthetic and natural resins, various three barks, piths and woods, such as cork, sugar cane stalks, cornstalks, wheat shafts, cotton seed hulls and linters, cotton stalks, pressed oat hulls and other vegetable or plant stalks or hulls, paper, rubber, felt, silk, cotton, rayon, nylon, linen, wool, coal tar products and other suitable ingredients, and also include synthetic resins of the thermoplastic type, such as the acrylate resins manufactured by Röhm-Haas Co., Philadelphia, Pa., under the name of "Rhoplex"; or by the Du Pont Co., Wilmington, Delaware, under the name of "Methacrol"; or thermo-setting types such as "Bakelite," which is manufactured by the Bakelite Corporation; or "Rhonite," which is manufactured by Röhm-Haas Co., Philadelphia, Pa.

An alternative way of preparing the discs 12 or 12a is to prepare a mixture of material, ground to the same degree of fineness, with substantially the same quantity of adherent, used in preparation of the rod-making material just described. The said mixture is then spread over a surface in sufficient thickness to reduce to the required thickness of disc 12 or 12a when subjected to a high pressure substantially equal to that used in packing the tubes of the first-described process forming thus a sheet 11 of material. This sheet while under pressure is subject to the same heat treatment described with respect to the first process and, after cooling, is removed from the pressure machine and stamped or otherwise cut into the discs 12 or 12a with any suitable apparatus.

In the case of preparation of sheets of material to be cut into discs, if desired, pressing flat by a rolling or other operation on the peanut shells or hulls, or on the cotton seed hulls may be substituted for the grinding up thereof. Otherwise, the process of sheet preparation remains the same as that for ground material. The same is true with respect to bagasse.

Discs 12 or 12a are then treated or coated in one of the ways described above and attached, also as described, in the respective caps 10 or 10a.

In a specific example of preparation of crown caps embodying the invention, 20 grams of peanut shells or hulls ground to pass through 12½ mesh screen were intimately mixed with 12 grams of albuminous binder known as Crown binder, prepared by the Consolidated Cork Corp., of Brooklyn, N. Y., and used presently for the preparation of cork composition discs, or other presently known crown binders. Other binders such as suitable dextrine adhesives, e. g., those manufactured by Stein Hall & Co., New York, N. Y., or Corn Products Refining Co., New York, may be used. This mixture was inserted into a metal tube having an internal diameter of approximately 1 and $\frac{1}{8}$ inches and subjected to a pressure of 2000 lbs. being heated gradually while under that pressure to from 145° F. to 200° F. over a period of one-half hour. Thereafter, still under pressure, the material was allowed to cool slowly and when cool the rod thus formed was removed from the metal tube. Discs having a thickness of approximately $\frac{1}{8}$ of an inch were then sliced from this rod. Each of these discs was then coated with paraffin or the aforementioned liquid vegetable wax by spraying thereon or dipping the discs in a bath of one of these

materials. Discs so treated were then adhered to crown caps 10a in the position shown in Fig. 3 after suitable application to the abutting faces of the discs and caps of one of the aforementioned adherents, namely, "Casco" glue. The caps 10a so provided were then ready for use on bottles.

The materials of discs 12 or 12a are applicable to other types of closures. Fig. 6, for example, illustrates a conventional type of closure used on catsup and other types of bottles. It usually comprises a metallic disc 18 to which is adhered a sealing and cushioning disc 19 which rests directly on the lips 20 of the bottle. The composite discs 18 and 19 are maintained in sealing relationship on the bottle by the removable clamping member 21. As long as the latter is undisturbed it serves to maintain the hermetic seal. Once the bottle has been opened the screw cap 22 alone serves as the closure to prevent access of dirt to the bottle contents.

The cushioning disc 19 heretofore has been made of cork. In place thereof, discs of similar shape prepared in the same way and comprising either the material of disc 12 with a facing of the same material as disc 14 can be used, or a disc of the material of disc 12a similarly treated with or without a facing disc may be attached, suitably to the metallic disc 18 serving as an adequate replacement for the now scarce cork and meeting all the requirements noted hereinabove.

Discs of the materials of discs 12, 12a and 19 also are capable of use in ordinary screw cap covers in place of conventional cork or paper gaskets.

It is to be understood that this invention may be modified in detail without departing from the spirit thereof. There is no intention of limitation to the exact details shown and described.

What is claimed is:

1. In a bottle closure of the type having a metallic crown cap, a sealing and cushioning member within said cap comprising a disc made of peanut shells or hulls in highly compressed ground form held together by a binder.
2. In a bottle closure of the type having a cap, a sealing and cushioning member adhered thereto, said member comprising a disc of ground peanut shells or hulls and a binder, said shells or hulls and said binder being highly compressed.
3. In a bottle closure of the type having a cap, a sealing and cushioning member adhered thereto, said member comprising a multi-ply disc at least one of whose plies is of ground peanut shells or hulls in compressed condition and held together by a binder, and another of whose plies is of liquid- and gas-impermeable material.
4. In a bottle closure of the type having a metallic crown cap, a sealing and cushioning member adhered thereto and comprising a disc of particles of ground compressed peanut shells or hulls and a binder for holding said particles together.
5. In a bottle closure of the type having a metallic crown cap, a sealing and cushioning member adhered thereto and comprising a disc of particles of ground compressed peanut shells or hulls capable of passing through 12½ mesh screen and a binder intimately mixed with said particles and serving to hold the latter together.

HERMAN M. KULMAN.
